UNITED STATES PATENT OFFICE.

GEORGE T. LADD, OF PITTSBURGH, PENNSYLVANIA.

VERTICAL WATER-TUBE BOILER.

1,238,530.

Specification of Letters Patent. Patented Aug. 28, 1917.

Application filed January 21, 1915. Serial No. 3,531

To all whom it may concern:

Be it known that I, GEORGE T. LADD, residing at Pittsburgh, in the county of Allegheny and State of Pennsylvania, a citizen 5 of the United States, have invented or discovered certain new and useful Improvements in Vertical Water-Tube Boilers, of which improvements the following is a specification.

- 10 In the accompanying drawings forming a part of this specification, Figure 1 is a side elevation of an upper drum of a vertical water tube boiler having my improved supporting means applied thereto; Fig. 2 is an 15 end elevation of the construction shown in Fig. 1; Figs. 3 and 4 are end and side views respectively illustrating a modification in the form of support; Figs. 5, 6 and 7, 8 are views similar respectively to Figs. 3 and 4, 20 illustrating further modifications of the supporting means; Fig. 9 is an end elevation of a drum supported by a strap extending underneath the drum; Figs. 10 and 11 are views similar to Fig. 3, illustrating 25 certain modifications and Fig. 12 is a sectional elevation of a complete boiler arranged in its setting and showing my improved manner of suspension.

The invention described herein relates to 30 that type of boiler consisting of upper and lower drums and tubes more or less vertical, connecting said drums. It is desirable and is generally the practice to support the upper drum by which the lower drum is supported through the medium of the tubes, thus allowing the tubes and lower drum to move freely. It has been the practice to support the upper drum by means of saddles forming portions of the end walls of the 35 boiler setting, the shell of the boiler resting in said saddles at points closely adjacent to its ends. In such an arrangement the ends of the upper drum are outside of the setting, an arrangement at times very undesirable. 40 When it is required that the upper drum should be wholly within the setting, two forms of support have been employed. In one case brackets are riveted to the heads of the upper drum and rest on the end walls 45 of the setting, so that these heads are subjected not only to the pressure of the steam in the drum but to strains incident to carry-

ing the entire weight of the boiler and the water. In the other form of support, channel bars or I-beams are arranged above and 55 at right angles to the drum and rest on the side walls of the setting and to these bars or beams are secured straps riveted to the sides of the upper drum. While this latter arrangement will relieve the heads of the 60 drum from the double strains above mentioned, it is objectionable as necessitating a greater height of boiler room to afford the necessary head room for the boiler.

The invention described has for its object 65 a construction in which the boiler supports are arranged below the highest part of the upper drum and are attached to the sides of the latter.

In the practice of my invention the supporting beams 2 which may be either two channel sections as shown in Figs. 1 to 9, inclusive, or a single channel section as shown in Fig. 10 or an I-section as shown in Fig. 11 are arranged parallel with the axis 75 of the upper drum 3 of the boiler and have their ends supported by the end walls of 80 the boiler setting. It is preferred that the ends of the beams should be directly supported by a girder 4 forming portions of the end walls of the setting. The end walls of 85 the setting are made of such a height and the beams 2 of such a depth that when the boiler is in position the upper edges of the beams will not be above the highest part of the boiler as for example the steam nozzle 5. It is preferred that the edges should be substantially below the highest portion of the 90 upper drum.

The invention as expressed in the broader 90 claims is not limited to any specific construction of the connections between the drum and the supporting beams, as many forms of such connection in addition to those shown herein will readily suggest themselves 95 to one skilled in the art.

In the construction shown in Figs. 1 to 4, pieces of metal are so slotted, bent and riveted to the shell of the drum as to form loops 6 for the reception of pins 7, which are also 100 passed through eyes 8 for the strap 9. In the construction shown in Figs. 1 and 2 the strap consists of strips of metal suitably bent and having their upper ends secured

between the channel sections forming the support beams by pins passing through straps and beams 2.

In the form shown in Figs. 3 and 4 the 5 straps 9^a have the eyes for the reception of the pins 7 forged on one end and the opposite ends threaded for the reception of nuts 10 bearing on cross pieces resting on the upper edges of the beams.

10 In the construction shown in Figs. 5 and 6, a U-shaped strap 9^b is employed, the closed 50 end of the strap being arranged in loops 6^a formed by suitably bending and riveting pieces of metal to the shell of the drum. The 15 legs of the U-shape pass up between the channel sections forming the beams and have their ends threaded for the reception of nuts 10, which as in the construction shown in Figs. 3 and 4 bear on cross-pieces 20 resting on the upper edges of the beams.

In the construction shown in Figs. 7 and 8, the straps 9^c connecting the drum to the beams consist of strips of metal having one end riveted to the boiler while the opposite 25 ends extend up between the members of the beams and are bolted thereto.

In lieu of connecting the drums to the supporting beams by means of straps attached to the shell by means of rivets, the 30 drum may rest in the loop of U-shaped bars 11, the legs of which extend up along opposite sides of the drums and between the channel sections of the beams as shown in Fig. 9. The protruding ends of the legs are 35 threaded for the reception of nuts 10, which as in the forms shown in Figs. 3 and 5 bear on plates laid across the upper edges of the beams.

If the boiler is small, and therefore the 40 load to be carried by the beams comparatively light, the beams may be formed of single channel bars 2^a as shown in Fig. 10, in which the straps connecting the drum and beams, will by preference be riveted to the 45 beams. And further the beams 2^b may be formed I-shape as shown in Fig. 10, in which case, the inner lower flanges of the shape will be notched to fit around the connection of the straps to the drum.

50 The number of connections between the drum and beams may be more than two on a side, and will generally be dependent on the length of the drum and the weight of the load carried by the upper drum. It will 55 be observed that in all the forms shown, except that illustrated in Fig. 9, the straps are connected to the drum above the longitudinal seams, a construction generally preferable, as seams and supporting parts are not subjected to flame and hot gases.

In order to protect the connections of the straps with the beams or drum from shearing strains as the boiler expands and contracts, the eye portions of the straps are 65 made sufficiently narrower than the distance

between the loops 6 on the drum thereby permitting of the independent longitudinal movement of the drum, as shown in Figs. 1 and 4. In the construction shown in Figs. 5 and 6 the portion of the U-shaped strap 70 engaging the loop on the drum is made sufficiently longer than the loop to permit the necessary expansion of the drum. In the construction shown in Figs. 7 and 8 where the straps are riveted to the drum the bolt 75 holes in the supporting beams or the straps or both are elongated so that the straps will slide along the beams as the length of the drum varies.

I claim herein as my invention: 80

1. In a boiler, the combination of an upper drum, tubes extending downwardly from the upper drum, a lower drum connected to and supported by said tubes, beams arranged substantially parallel with the axes of said 85 drums, and on opposite sides of the upper drum and adapted to rest at their ends on the boiler setting, and means for connecting the upper drum to said beams which form the sole support of the boiler whereby the 90 boiler is free to move in its setting.

2. A boiler consisting of upper and lower drums and tubes connecting said drums in combination with beams arranged on opposite sides of the upper drum and in substantial 95 parallelism with the axis thereof and resting at their ends on the boiler setting, and means for so connecting the upper drum to the beams that the beams forming the sole support of the boiler will be below a 100 horizontal plane passing through the highest portion of the drum.

3. A boiler consisting of upper and lower drums and tubes connecting said drums, in combination with beams arranged on opposite sides of the drum and in substantial parallelism to the axis thereof and resting at their ends on the boiler setting, and straps attached to the beams and to the upper drum at points above a horizontal plane 110 coincident with the axis of the drum and adapted to so support the drum that the supporting beams will be intermediate the points of attachment of the straps and the highest portion of the drum. 115

4. A boiler consisting of upper and lower drums and connecting tubes in combination with beams arranged substantially parallel with the axes of the upper drum and on opposite sides thereof and adapted to rest at 120 their ends on the boiler setting, and means for suspending the upper drum between the beams forming the support for the boiler, the suspending means interposed between the drum and beams being adapted to permit of the movement of the boiler independent of the supporting beams. 125

5. In a boiler, the combination of an upper drum, beams arranged substantially parallel with the axis of said drum and on opposite 130

sides thereof, and adapted to rest at their ends on the boiler setting, means for suspending the upper drum from said beams, a lower drum, and tubes connecting the upper 5 and lower drums and forming the sole support for the latter.

In testimony whereof, I have hereunto set my hand.

GEORGE T. LADD.
